SPECIFICATION forming part of Design No. 17,437, dated July 12, 1887.

Application filed June 15, 1887. Serial No. 241,447. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

Large open flower figures are loosely scat-

tered over the face of the design and are connected on inconspicuous stems, the stems carrying also various leaf forms. In the lower left part of the photograph is a large figure 20 resembling a cornucopia.

The various features of the design are clearly shown in the photograph.

What I claim as new, and desire to secure by Letters Patent, is—

The design for a carpet, consisting of the 25 design substantially as shown.
